UNITED STATES PATENT OFFICE.

GEORGE L. REICHHHELM, OF NEW YORK, N. Y.

GASIFYING MECHANISM.

Application filed January 11, 1919. Serial No. 270,694.

To all whom it may concern:

Be it known that I, GEORGE L. REICHHHELM, a citizen of the United States, residing at New York, in the county of New York and State of New York, have invented certain new and useful Improvements in Gasifying Mechanism, of which the following is a specification.

This invention relates to gasifying mechanism, and more particularly to a combination of parts, in one of which parts a gas is produced from a heavy hydro-carbon for starting an internal combustion engine, the products of combustion from the internal combustion engine, in turn heating another one of the parts in which a heavy hydro-carbon may be gasified preparatory to being supplied to the engine for power purposes, the use of light hydro-carbons such as gasoline, thereby being entirely obviated.

One of the objects of this invention is to make it possible to start an internal combustion engine on relatively heavy hydro-carbons.

Another object is to provide a novel gasifier arrangement, by means of which an internal combustion engine may be started and operated on heavy hydro-carbons.

Another object is to provide a novel combination of producer plant and carbureter adapted to meet all starting and operating conditions for internal combustion engines operating on heavy hydro-carbons.

These and other objects are accomplished by means of the arrangement disclosed on the accompanying sheets of drawings, in which—

Figure 1 is a side elevation of my gasifying mechanism, parts being in section for the sake of clearness;

Figure 2 is a plan view of the same arrangement showing also a portion of an engine;

Figure 3 is an end view of the mechanism shown in Figure 1;

Figure 4 is a detail view showing an operative connection to an oil controlling valve;

Figure 5 is a perspective view of the air control piston;

Figure 6 is a perspective view of the sleeve which is associated with the air control piston;

Figure 7 is a detail sectional view showing the arrangement for separating and spreading the liquid fuel into thin films; and,

Figure 8 is a detail view of the combination air and oil control valve for the primer or liquid producer plant.

The various novel features of my invention will be apparent from the following description and drawings and will be particularly pointed out in the appended claims.

In my copending application, Serial No. 270,693, filed January 11, 1919, I have disclosed a liquid fuel producer in which relatively heavy hydro-carbon is supplied through a tube and to a plurality of legs connected therewith, said legs being provided with spaced pieces of mica, parts of which are located within the tube legs for collecting the oil, the oil by capillary attraction passing along the mica and dividing into thin films exteriorly with respect to the legs, the lower films of oil being treated by an electric spark whereby a portion thereof is gasified and ignited to gasify and ignite the remaining films of oil on the other mica strips, thus producing a hot flame for heating the tube and its legs through which a continuous supply of heavy hydro-carbon passes, this heavy hydro-carbon thereby becoming gasified and being passed with a certain amount of air and products of combustion through the casing of the producer, from which the same may be directed to any proper device for suitable purposes.

In this present application I disclose the liquid fuel producer above mentioned in connection with a carbureter for an internal combustion engine, the liquid fuel producer in effect acting as a primer for starting the engine, after which the liquid fuel producer is cut out of action and the engine run on the same grade of heavy hydro-carbon preferably supplied from another source, it being understood that the engine is started from a cold condition on a heavy hydro-carbon, as well as being run on a heavy hydro-carbon.

Referring to the figures of the drawings, it will be noted that my gasifying mechanism includes the liquid producer plant described and claimed in the copending application hereinabove referred to and includes

a casing 10 which is provided with an opening 9 for the reception of a tube 11 which branches into two downwardly extending legs 12 having closed ends. The upper extremity of the tube 11 terminates in a valve casing 13 having an air inlet 14, there being a valve 15 operable within the valve casing 13 to control the supply of air to the tube 11 and its legs 12. This valve 15 also controls the flow of heavy hydro-carbon which is supplied to the tube 11 through a pipe 16, the fuel and air passing in groove 17 of the valve. It will be understood that when air is caused to pass downwardly into the tube 11 and legs 12, the liquid fuel also will pass through the tube 11 and legs 12.

In order to efficiently gasify a heavy liquid fuel initially, I have caused the liquid fuel to be separated into relatively thin films, after which said films of oil may be treated with heat for gasification preparatory to ignition. For spreading or separating the relatively heavy liquid fuel into relatively thin films, I have provided each of the legs 12 with bunches or groups of spaced mica 18, the middle portion of the bunches extending through suitable openings 19 on the inner sides of the legs, said openings 19 in each leg being in vertical alignment, the set of openings 19 in one leg being opposite the set of openings 19 in the other leg. The arrangement of a single bunch of mica is shown in Figure 7, in connection with which it will be noted that the sheets of mica are spread widely within the leg 12 for receiving or collecting the liquid fuel as it passes downwardly through the leg 12. As a result of capillary attraction, the liquid fuel gathered by the mica within the legs 12 is passed outwardly along the mica strips, forming relatively thin films of liquid fuel between and on the outwardly diverging pieces of mica which extend outwardly from the legs 12 into the casing 10. A spark plug 20 is secured to the casing 10 adjacent one of the lower bunches of mica. Between the two poles formed by the spark plug wire 21 and a sheet metal strip 22, some of the mica is interposed, and in view of the fact that the mica is a non-conductor, it diverts the produced electrical spark, the spark first impinging upon the mica in its attempt to take the shortest course. This heats a small portion of the non-conductor, vaporizing the liquid fuel thereon and almost simultaneously causing a flame. The arrangement and spread of the mica leaves, as shown in the drawings, causes the flame to travel upwardly and spread to the other leaves. At this point it will be noted that the legs, intermediate the bunches of mica, are provided with holes 23, the series of holes 23 in one leg being located directly opposite the series of holes in the opposite leg. The air which passes downwardly through the

legs 12 and outwardly through these openings 23 necessarily has the same velocity, and where these streams meet the velocity, irrespective of the speed from the orifices, must be zero. In this way it is possible to cause combustion with a high or low velocity, or with a high or low pressure, which to all intent in this process is the same. It will be understood that the flame originally formed at the lower bunch of mica will spread rapidly upwardly, gasifying the liquid fuel in the mica sheets arranged above, this being especially true in view of the fact that a definite amount of air is supplied through the openings 23 for supporting combustion. It will be understood that the large and relatively hot flame thus produced will act upon the tube 11 and legs 12 for gasifying the liquid fuel continuously passing therethrough. The products of combustion formed by this heating action pass upwardly through the vertical portion of the casing 10 and laterally through the horizontal portion of said casing, and pass outwardly through the casing opening 24. It also will be understood readily that if an excess amount of oil is permitted to flow through the tube 11 and legs 12, a gaseous vapor will pass through the casing to the outlet 24, which when mixed with the proper supply of air will readily produce an extremely hot flame for the desired purpose. It is readily apparent that when the fuel distributed in the fan-shaped lamination of mica is afame and streams of air are being issued through the openings or orifices 23, an exceedingly high temperature can be developed, and as a result thereof it will not be difficult to understand why it has been possible, by turning on an excess amount of liquid fuel, that a gaseous vapor will be formed which will issue from the casing opening 24.

In the drawings I have shown this liquid gas producing plant as used in connection with a carburetor for an internal combustion engine, the liquid fuel producer in effect being used as a primer for starting the engine in a cold condition on a heavy hydro-carbon, such as kerosene. After the engine has been started and has warmed up sufficiently, the liquid fuel producer may be rendered inoperative and the engine receive its combustible charge from another source of supply.

Referring particularly to Figure 1 of the drawings, it will be noted that the upper part of one of the legs of the U-shaped tube 25 is extended through the casing opening 24 so that the gas produced in the producer plant or primer may pass through the U-shaped tube 25 into the union 26, which has an air connection 27 whereby the gas and air may be mixed in union 26 and passed through conduit 27 and inlet manifold 28

to the cylinders of the internal combustion engine 28', wherein the explosive mixture will be compressed, ignited and expanded for doing work. The resulting products of 5 combustion pass out of the engine cylinders through the exhaust manifold 29 and conduit 30, in the lower part of which the gasifying U-shaped tube 25 is located, the hot exhaust gas then passing outwardly 10 through conduit 31. It will be understood that these hot exhaust gases in passing through the conduit 30 heat the gasifying tube 25 and maintain the same in a hot condition. In this connection it will be appreciated 15 that if a liquid fuel, such as kerosene, or any other relatively heavy hydro-carbon, is passed into the tube 25, it immediately will become vaporized and gasified. The U-shaped tube 25 is provided with a series 20 of baffles 32, which are arranged alternately and extend into the center of the tube, thereby causing the gas thus formed in the tube to take a serpentine course and to become thoroughly mixed. If the tube is maintained 25 at the proper temperature, as it will be during the regular operation of the engine, the gas issuing from the tube 25 will be fixed. In this connection it will be noted that only the fuel gas will be heated to a relatively 30 high temperature and when it becomes mixed with cold air in the union 26, the resulting combustible mixture will be cooled considerably to occupy the minimum amount of space preparatory to passing into the cylinders 35 whereby the volumetric efficiency will be increased.

As stated above, the engine is started upon a gas formed in the liquid producing plant or primer, said gas passing through the casting 40 10 and into the U-shaped tube 25, and from there on through the cycle heretofore described. To produce the gas in the liquid producing plant it is necessary that the electric circuit for the spark plug be complete. 45 Normally it is incomplete, which is caused by the separation of relatively stationary contact 33 and movable contact 34, which is supported in a lever 35 which may be controlled by the operator through any suitable 50 control member, such as 36. This control member 36 also controls the supply of heavy hydro-carbon and air to the primer for supplying the initial charges of combustible mixture to the engine cylinders, said 55 control being made possible by the connection 37 from the lever 35 to the valve 15, which regulates both the supply of air and liquid fuel. Accordingly, when it is desired to start the engine, it is merely necessary to 60 pull the control member 36, whereupon oil and air are supplied to the producer plant and the electric circuit completed for furnishing the necessary heating and ignition spark. After the liquid producer plant has 65 served its function in starting the engine,

the control member 36 may be released, whereupon the supply of oil and air to the primer automatically will be shut off and the electric circuit of the spark plug automatically broken. It will be understood that as 70 soon as the products of combustion are exhausted through the exhaust manifold and conduit 30, the gasifying tube 25 of the main carbureter will be highly heated for gasifying a heavy liquid hydro-carbon which 75 may be passed therethrough. Heavy hydro-carbon supplied to the engine for regular running is furnished from a member 38 and supply pipe 39 located over one leg of the U-shaped gasifying tube 25 so that any hydro-carbon which is discharged through the pipe 39 will pass into the U-shaped tube and will be gasified and fixed therein preparatory to being mixed with the cold air in the union 26. This supply of oil is controlled 80 by a valve 40 having an arm 41 which is connected to rods 42 relatively adjustable with respect to each other through a turn buckle 43, one of said rods being connected to the lever 41 and the other being connected to a lever 44 selectively through any one of a number of openings 45. The supply of air which is mixed with the gas in the union 26 is controlled by a valve in the form of a piston 46, which is operable within an open 85 ended sleeve 47 adjustable vertically within a casing 48 forming a part of the carbureter structure. The piston valve 46 is provided with an opening 46' so that when the piston valve is raised upwardly beyond the upper 90 rim 49 of the sleeve 47, cold air will be supplied upwardly through the sleeve 47, through piston opening 46', conduit 27, and into union 26, where the fixed gas and air may be mixed in the proper 95 proportion for forming a combustible mixture preparatory to passing into the cylinders of the engine. Any suitable number of openings 46' may be provided, and preferably the lower portions thereof are contracted, 100 such being necessary because the greater velocity at high speed causes a greater flow in volume of air. The taper in this case was determined by experiment.

The friction caused by the gas passing 115 through the U-shaped tube 25 makes it necessary to supply friction to the passage of the larger volume of air entering through the piston valve 46, and since this necessitates the introduction of a moving part, 120 I have provided an arrangement for automatically regulating the inflow of the hydro-carbon, at the same time keeping both the charges of hydro-carbon and the charges of air synchronized. Accordingly, I have 125 formed a connection between the air piston valve 46 and the fuel inlet valve 40, the connection including a link 50 connected to the piston valve 46 and to a lever 51, the lever in turn being connected to a shaft 52 130

to which the lower end of the lever 44 is connected. The shaft 52 is supported in a bracket 53, which is secured to the pipe 27 of the carbureter structure. From this arrangement it is apparent that any motion of the piston valve 46 will give the corresponding motion to the needle or oil controlling valve 40. When the turn buckle 43 is adjusted, the two valves will remain synchronized. When in rest position, as shown in Figure 1, the oil is shut off. This obviates the use of a float tank and its attendant troubles. It will be understood, of course, that the piston valve 46 is raised to permit a supply of air as a result of the suction caused by the suction strokes of the engine pistons. A throttling device 54 for the piston valve 46 is diagrammatically shown, said throttling device holding down the lever 51, and when lifted allows the piston valve to rise, and in proportion to the rise of this piston valve, the lever 51 will be actuated to convey a definite amount of motion to the oil control valve 40. To lessen the speed, the lever 54 is forced downwardly, preventing the flow of fuel and air. If the engine is stopped by throwing off the spark, or for any other reason, the weight 55 on the lever 51 will carry the piston valve 46 downwardly and shut off the oil supply.

Among other things, by means of this gasifying mechanism, including a liquid producer plant or primer for gasifying a heavy hydro-carbon for an initial supply of combustible gas and means for gasifying a different supply of heavy hydro-carbon for the charges of combustible gas for starting an internal combustion engine in a cold condition and operating the same on heavy hydro-carbon, an efficient device is provided adapted to meet the requirements for operating internal combustion engines on the relatively heavy hydro-carbon fuels.

It is my intention to cover all modifications of the invention falling within the spirit and scope of the following claims.

I claim:

1. In combination, an internal combustion engine including exhaust means therefor, producer means for gasifying heavy hydro-carbon for an initial supply of combustible gas, means for gasifying heavy hydro-carbon from a different source for supplying combustible gas, said engine exhaust means being placed in a position to provide heat for said second mentioned means, and means for supplying air for mixture with said combustible gas, said engine exhaust means being placed in position to fix said gas before said gas is mixed with said air.

2. In combination, a casing having a pair of inlets for fuel, an outlet conductor, means comprising the exhaust member of an internal combustion engine for heating said outlet conductor, feed means for supplying

heavy hydro-carbon through one of said inlets substantially directly to said outlet conductor and vaporizing means adjacent to the other of said inlets for vaporizing heavy hydro-carbon for starting purposes.

3. In combination, a conductor for fuel, means comprising the exhaust member of an internal combustion engine for heating said conductor, feed means for supplying heavy hydro-carbon substantially directly to said conductor and vaporizing means for vaporizing heavy hydro-carbon and delivering the resulting gas to said conductor for starting purposes.

4. In gasifying mechanism, the combination of air supply means, a member connected thereto, producer means for gasifying a heavy hydro-carbon for an initial charge of gaseous fuel which passes through said member preparatory to mixing with air from said air supply means, means whereby a second heavy hydro-carbon supply may be gasified in said member preparatory to mixing with air from said air supply means, and interconnected control means for the air supply and the second mentioned supply of heavy hydro-carbon.

5. In combination, an internal combustion engine having an intake conductor, means for supplying heavy hydro-carbon substantially directly to said conductor, means for gasifying heavy hydro-carbon and supplying same to said conductor for starting purposes, said conductor being placed in a position to be heated by the exhaust product of said engine, whereby gases flowing through said conductor may be fixed, and means for supplying air to said gases at a point beyond the fixing point of said gases.

6. In combination, an internal combustion engine, a source of relatively heavy hydrocarbon fuel, producer means for gasifying said fuel, means for leading said gasified fuel to said engine, means operatively associated with the exhaust manifold of said engine for communicating heat to said leading means, means for supplying said relatively heavy fuel directly to said leading means independently of said producer means, common means for controlling the operation of said producer means and for controlling the supply of said heavy fuel and means for admitting air to said gasified fuel at a point in the passage of said gasified fuel after said gasified fuel has been subjected to heat from said means operatively associated with said exhaust manifold.

7. In combination, an internal combustion engine, a source of relatively heavy hydro-carbon fuel, producer means for gasifying said fuel, means for leading said gasified fuel to said engine, means operatively associated with the exhaust manifold of said engine for communicating heat to said leading means, means for supplying said rela-

tively heavy fuel directly to said leading means independently of said producer means, common means for controlling the operation of said producer means and for 5 controlling the supply of said heavy fuel, and means for supplying air for mixing with said gasified fuel, said heat communicating means being placed in position to fix said gasified fuel before said fuel is mixed 10 with said air.

8. In combination, an internal combustion engine, means for supplying air thereto, means for conducting heated gases from said engine, means for leading combustible gas to 15 a point in communication with said air supply means for delivery to said engine, said heated gas conducting means being placed in a position to fix said combustible gas before said gas is mixed with the air from 20 said air supply means, means for supplying relatively heavy hydrocarbon fuel, means for gasifying said fuel to form a combustible gas and delivering same to said leading means, means for delivering relatively heavy 25 fuel directly to said leading means independently of said gasifying means, and common

means for controlling said air supply means and the supply of said heavy fuel.

9. In combination, an internal combustion engine, means for supplying air thereto, 30 means for conducting heated gases from said engine, means for leading combustible gas to a point in communication with said air supply means for delivery to said engine, said heated gas conducting means being 35 placed in a position to fix said combustible gas before said gas is mixed with the air from said air supply means, means for supplying relatively heavy hydrocarbon fuel, means for gasifying said fuel to form 40 a combustible gas and delivering same to said leading means, means for delivering relatively heavy fuel directly to said leading means independently of said gasifying 45 means, and common means for controlling the operativeness of said vaporizing means and for controlling the supply of heavy fuel.

Signed at New York, New York, this 7th day of Jan'y, 1919.

GEORGE L. REICHHLEM.
